UNITED STATES PATENT OFFICE.

GEORGE H. HULETT, OF CLEVELAND, OHIO, ASSIGNOR TO THE WELLMAN-SEAVIER-MORGAN COMPANY, OF CLEVELAND, OHIO.

CAR-DUMPING MECHANISM.

1,084,437.

Specification of Letters Patent.

Patented Jan. 18, 1914.

Application filed June 2, 1913. Serial No. 771,291.

To all whom it may concern:

Be it known that I, GEORGE H. HULETT, of Cleveland, in the county of Cuyahoga and State of Ohio, have invented certain new and useful Improvements in Car-Dumping Mechanism; and I do hereby declare the following to be a full, clear, and exact description of the invention, such as will enable others skilled in the art to which it appertains to make and use the same.

This invention relates to improvements in car dumping mechanism, the object of the invention being to provide simple and efficient means for facilitating the raising, tilting and lowering of the car-carrying cradle, and to reduce to a minimum the power necessary to accomplish these operations.

With this and other objects in view, the invention consists in certain novel features of construction and combinations of parts as hereinafter set forth and pointed out in the claims.

The accompanying drawing is a diagrammatical view illustrating an embodiment of my invention.

1 represents a cradle comprising a platform 2 onto which the car to be dumped will be run, and a vertical portion 3, the latter being provided with rollers, such as indicated at 4, to run in upright guides 5 and said cradle is also provided with rollers, such as indicated at 6, to run on upright guides 7. Each guide 5 is made with an outwardly projecting portion which may be curved as shown at 8 and at the end of this curved upper part of the guide, a curved stop 9 is provided. The guide 7 is provided at its upper portion with an inwardly or rearwardly projecting part 10 which forms a cam-portion 11 for the upper part of said guide 7. The guides 5-7 are secured to and carried by a horizontal beam 12 which is vertically movable in any suitable framework,—screw 13 being provided for adjusting said beam vertically, and these screws may be operated through gears 14-15 from any convenient source of power connected with the shaft 16 to which the gear 15 is secured. An apron 18 is connected with the beam 12 and is intended to receive material dumped from a car and deliver it through a suitable chute or conveyer to the hold of a boat.

The cradle 1 is provided with depending brackets 19-20 in which pulleys 21-22 are

mounted for the passage of lifting cables 23. Each lifting cable 23 is secured at one end to the beam 12 or rather to the upper end of each guide 5 (preferably at a point concentric with the curved stop 9). From its connection with the upper end of the guide 5, each cable 23 extends downwardly and, after passing over the pulleys 21-22 and under the cradle, said cable extends upwardly and passes over pulleys 24-25 located in a plane above that of the highest point of adjustment of the beam 12. From pulley 25, each lifting cable extends downwardly and is wound on a drum 26 to which power may be applied and the operation of which may be controlled by any suitable means. A cable 27 is connected with the cradle preferably at a point approximately concentric with each roller 4, and from such connection with the cable, each cable 27 extends upwardly and, after passing over pulleys 28-29 located above the plane of that to which the beam 12 is capable of being raised, the depending end of each cable 27 is provided with a weight 30.

Clamp-bars 31 (for clamping a car 32 to the cradle while the latter is being tilted during the dumping operations) are pivotally connected with the cradle preferably through the means of clamps 33,—said clamping-bars and clamps and means for controlling the operation of the latter to engage a car, being well-known in the art. A cable 34 is connected with the cradle (preferably through the medium of each clamp 33) and, after passing over clamp-bar 31 and under a pulley 35 at the free end of the latter, each cable 34 extends upwardly and over pulleys 36-37,—the free depending end of each cable 34 being provided with a weight 38.

The mechanism above described operates as follows: After a car has been located upon the cradle, power will be applied to the drum 26 to wind the cable 23 thereon, with the result of hoisting the cradle and car, such hoisting being assisted by the weights 30 and 38. This upward movement of the cradle and car continues until roller 6 passes over the cam portion 11 of guide 7 and the roller 4 arrives at the stop 9 at the upper end of guide 5 during which movement and while the roller 6 is passing over the cam guide 11, the cradle will be tilted on the pivotal support afforded by the bearing of 110

roller 4 at the upper end of the guide 5—8. Continued rotation of the drum 26 will cause the cradle to be fully tilted on said pivotal support and the contents of the car to be inverted and thus caused to discharge its contents onto the apron 18. During such tilting of the cradle, the clamping bars 31 will be caused to become disposed across the open top of the car as will be readily understood. 5 When the contents of the car have been discharged, release of the drum 26 will permit the cradle to be drawn back by the operation of the weights 38 connected with the clamp beams and the cradle may then be lowered 10 under the control of the suitable brake device applied to the drum 26. During such lowering of the cradle, the weights 30 and 38 will be raised. It will be observed that by elevating the beam 12, the guides 5 and 7 and the apron 18 will also be raised, and the 15 mechanism may thus be adapted to raise the cradle different heights according to the height of the boat into which the contents of cars is to be dumped. 20 With car dumping mechanism of the type to which my invention relates, as heretofore built, it was necessary to have two parts of rope on the side of the cradle carrying the pivot in order to prevent the cradle from swinging out instead of hoisting, when the drum was rotated and after the cradle was lifted until it came in contact with the pivot carried by the girder, more power was necessary to rotate the car 25 than was required to lift it, and it was necessary to take in three parts of cable when lifting and only one part of cable when revolving, the result was that a very serious increase in power was required to lift it, and 30 at the same time, the speed of the machinery was only one-third that required to lift it. This made it necessary to stop hoisting the cradle when it came in contact with the pivot and then start the machinery again 35 under greater loads at about one-third speed. These objections are obviated in my improved construction, by the provision of counterweight 30 and the employment of cable in two parts for hoisting instead of one, the counterweight taking one-third of the weight to be lifted and the change of speed being only from one to two instead of one to three. To further decrease the power required to hoist and turn the car, and to 40 save the loss of time by reason of stopping the car when the cradle comes in contact with the pivot bearing and avoiding the shock and the very large increase of power necessary to turn the cradle, I have designed 45 the guides 5—7 which, as before explained, are attached to the girder and operate to partially invert the car before it reaches the pivot, and as the center of the gravity of the car, its contents and the cradle, has 50 now passed very much nearer to the pivot around which it is to be revolved, the power required to turn the load is reduced to a minimum, permitting a higher speed of turning with the same sized motors or engines, than has heretofore been accomplished. 70 The combined weight of the counterweights 30 and 38, is less than the weight of the empty cradle and the cradle will therefore remain in its normal position 75 without being latched and the combined weight of an empty car and the cradle is sufficient to hoist the counterweights and permit the cradle to descend under control of the drum 26. 80 Various changes might be made in the details of construction of my invention, without departing from the spirit thereof or limiting its scope and hence I do not wish to restrict myself to specific structural details. 85 Having fully described my invention what I claim as new and desire to secure by Letters-Patent, is:—

1. In car dumping mechanism, the combination of a cradle, vertically adjustable guides therefor, a counterweighted cable connected with the cradle, and a counterweighted cable connected with a normally fixed support and having movable connection with the cradle under the same. 90
2. In car dumping mechanism, the combination with a vertically adjustable beam and a cradle, of guides for the cradle attached to and movable vertically with said beam, and means for raising, lowering and tilting said cradle. 100
3. In car dumping mechanism, the combination with a horizontal beam and a cradle, of guides for the cradle connected with and depending from said beam, means for raising and lowering said horizontal beam and the guides connected therewith, and means for raising, lowering and tilting said cradle. 105
4. In car dumping mechanism, the combination with a cradle, a horizontal beam and means for adjusting the beam vertically, of guiding means for the cradle connected with said beam, a cable secured at one end to said beam and formed into a loop having movable connection with the cradle, and means for operating said cable. 110
5. In car dumping mechanism, the combination with a cradle, a horizontal beam, 120 and means for adjusting the beam vertically, of guiding means for the cradle connected at one end with said beam and formed into a loop having movable connection with the cradle, means for operating 125 said cable, and a counterweighted cable connected with the cradle in proximity to said guiding means.
6. In car dumping mechanism, the combination with a beam, and a cradle, of a 130

guide for the cradle, said guide having an outwardly curved upper end attached to said beam, said upper end of the guide having a stop constituting a pivotal support for the cradle, means for raising, lowering and tilting the cradle, and means for adjusting said beam vertically.

In testimony whereof, I have signed this specification in the presence of two subscribing witnesses.

GEORGE H. HULETT.
